(57) **CLAIM**

The ornamental design for a training shoe as shown and described.

DESCRIPTION

FIG. 1 is a perspective view of the training shoe of the present invention showing our new design;

FIG. 2 is a left side elevational view thereof;

FIG. 3 is right side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of a second embodiment of the training shoe of the present invention showing our new design;

FIG. 9 is a left side elevational view thereof;

FIG. 10 is a right side elevational view thereof;

FIG. 11 is a top plan view thereof;

FIG. 12 is a bottom plan view thereof;

FIG. 13 is a front elevational view thereof; and,

FIG. 14 is a rear elevational view thereof.

The dotted lines shown on the shoe upper in the figures indicate stitching.

The dotted lines shown on the shoe sole in the figures form no part of the claimed design.

The diagonal shading shown in the figures indicates transparent material.

1 Claim, 8 Drawing Sheets
